UNITED STATES PATENT OFFICE

160,917

WATCH BRACELET OR SIMILAR ARTICLE

Karl C. Augenstein, Cranston, R. I., assignor to
Speidel Corporation, a corporation of Rhode
Island

Application June 8, 1950, Serial No. 10,413

Term of patent 14 years

(Cl. D45—4)

To all whom it may concern:

Be it known that I, Karl C. Augenstein, a citizen of the United States of America, residing at Cranston, county of Providence, and State of Rhode Island, have invented a new, original, and ornamental Design for a Watch Bracelet or Similar Article, of which the following is a specification, reference being had to the accompanying drawing, forming a part thereof.

Fig. 1 is a top plan view of a watch bracelet or similar article, showing my new design, the end connecting links being shown in dot-dash; and

Fig. 2 is a side elevational view of the bracelet looking from bottom to top at the bracelet shown in Fig. 1.

The dominant features of my design reside in the portions shown in full lines.

I claim:

The ornamental design for a watch bracelet or similar article, substantially as shown and described.

KARL C. AUGENSTEIN.
